COVER CLAMP

Ewald Schmitz, Milwaukee, Wis., assignor to A. O.
Smith Corporation, Milwaukee, Wis., a corpora-
tion of New York

Application December 5, 1951, Serial No. 259,959

4 Claims. (Cl. 292—256.73)

1

This invention relates generally to a clamp for use in connection with manway covers such as are generally used with large storage tanks for various liquid products. Specifically, the clamp of this invention will be described in association with a manway cover which may be used with a glass-lined tank for the storage of beer or the like.

One object of the invention is to provide a relatively simple clamp for use in connection with a manway cover for a tank in which a positive connection is afforded between the turning means employed and the clamp utilized in removably securing a manway cover to a tank in a desired location.

Another object is to provide a clamping means whereby the manway cover to which the means is applied is unlatched or latched in place without visual observation.

A further object of the invention is to provide clamping means of the above type in which a positive connection is afforded between the turning means employed and the clamp utilized whereby the latter will be positively moved from locked or locking position so that a removably secured manway cover may be easily and quickly removed from the container or tank to which it has been applied.

Another object is to provide clamping means for the manway cover of a vessel or the like which may be assembled with great facility, easily operated, and which permits ease of cleaning, thereby providing for desirable sanitation characteristics.

These and other objects will appear from the following description when taken in connection with the accompanying drawing, in which:

Figure 1 is a top plan view of a manway cover secured to a manway or the like by the clamps of this invention, with parts broken away for the sake of clarity;

Fig. 2 is a partial longitudinal sectional view of the clamp of the invention showing the clamp in a position to secure the manway cover to a manway;

Fig. 3 is a view similar to Fig. 2 showing the clamp backed off so that the hook disposed at the lower end of the clamp hook is disengaged from the annular flange disposed at the upper edge of a manway;

Fig. 4 is a view similar to Fig. 3 but showing the wing-nut turned 270° counterclockwise relative to the position of the wing-nut depicted in Fig. 3;

Fig. 5 is a view taken on line 5—5 of Fig. 2; and

2

Fig. 6 is a view taken on line 6—6 of Fig. 4. The following description will be limited to describing a single clamping unit in conjunction with a manway cover for a storage tank in which any suitable number of these units may be spaced about a vessel cover as best seen in Figure 1.

Briefly the invention comprises a clamping member for clamping a cover over an opening in the tank in which the clamping member is permitted limited longitudinal movement and is actuated by rotational movement of a threaded nut. The clamping member is provided with a stop or abutment at one end, which frictionally engages a second stop or abutment on the nut disposed in the path of movement of the clamping member, the clamping member being moved by rotation of the nut. The binding action between the two stop members causes a hook disposed at the end opposite the stop end of the clamping member to swing outwardly from under a flange member on the tank which releases the cover member from engagement with the tank. In tightening the cover in place the established binding action of the two stops causes the hook to immediately swing under the flange for engaging the flange and securing the cover in place. Each clamping member shown around the circumference is the same.

According to the invention a manway 1, which may be disposed either vertically or horizontally, and having a wall 2, is provided with an annular flange 3, extending outwardly from the upper edge of the wall.

Cover 4 is disposed at the outer end of the manway 1, and is shown as provided with spaced annular bearing cups 5, adjacent its outer edge, each formed by the apertured base 6 and the circular flange 7, the latter extending outwardly from and upwardly and normal to the outer rim of the cover.

Gasket 8 of any suitable material may be disposed between the flange 3 and the cover, and when compressed between the flange and the cover, provides an efficient seal between these members.

Adjacent the upper edge of the flange 7 a threaded aperture 9 is disposed radially through the flange for the reception of a hex-socket setscrew 10. The inner end 11 of set-screw 10 is disposed, when the clamp of the invention is assembled, in an annular groove 12 disposed adjacent the lower edge of the body of a wing-nut 13, as later described.

Wing-nut 13, provided with the usual handles 14, has a bore 15 extending longitudinally of the body 16 of the nut and is internally threaded at

11 from the lower edge of the nut, upwardly for a distance substantially midway the length of the body 16. The upper end 18 of the bore is reduced in diameter and is devoid of threads. The upper end of the bore is tapered inwardly at 19 and provides a bridge 20 intermediate the handles 14.

A threaded aperture 21, disposed above the aperture 9, extends radially through the body of the wing-nut, for the reception of a second hex-socket set-screw 22, the inner end 23 of which is disposed in the upper end of bore 18 when the set-screw is turned inwardly to serve its intended function.

Clamping hook 24 is provided with a smooth body 25 adjacent its lower end which is disposed in aperture 26 extending through base 6 of cup 5 and is adapted for vertical movement therethrough in response to turning of the wing-nut. The lower end of body 25 is provided with a hook member 27 which is adapted to seat against the lower surface of flange 3 of the vessel under certain operating conditions. Immediately above hook 27 and extending radially from body 25, and angularly offset from hook 27, a stop lug 28 is disposed so that it will engage the outer vertical edge of flange 3.

The mid-portion of body 25 is threaded at 29 in a direction to match the threads 17 of the wing-nut. The clamping hook is disposed in the bore of the wing-nut which in turn is aligned with the aperture in the base of the cup. Turning of the wing-nut, under conditions of restricted axial movement of the wing-nut, will cause the clamp hook to feed into or out of the wing-nut.

The clamping hook 24 is reduced in diameter from the threaded portion to adjacent the upper end of the clamping hook to provide a shoulder or abutment 30 at its upper end to be engaged by the inner end 23 of screw 22. The axial downward travel of the clamping hook is limited by the engagement of the shoulder 30 with the inner end 23 of the set-screw 22.

In assembling the clamp unit the wing-nut 13 is inserted into the bearing cup 5 in the manway cover member. Set-screw 10 is turned inwardly so that its inner end 11 enters the annular groove 12. The wing-nut is now free to turn in the manway cover while being held from moving in an axial direction. Next the clamping hook 24 is threaded into the wing-nut and set-screw 22 is turned inwardly so that its inner end 23 is at the reduced portion and under the shoulder 30 of the clamping hook.

To effect the clamping operation with the clamp of this invention after the clamps have been assembled on the cover and the cover is mounted on the tank, the hooks 24 are set respectively to positions as best seen in Fig. 6. This position might be termed the "unclamped position," and being thus disposed, the hooks will clear the manway flange when the cover is set in place. After the cover is set in place the hooks are turned clockwise until the stops 28 on the hooks meet the manway flange.

Each wing-nut is then given about one and one-half turns in a clockwise direction to draw up the hook and clamp the cover to the flange and compress the gasket 8 between the cover and the flange 3, so that a pressure-tight seal results. Since the rotation of the hooks 24 is halted by the stops 28, any further turning of the wing-nuts in a clockwise direction results in move-

ment of the hooks into the wing-nuts, with a resultant compression of the gasket.

To effect removal of the cover from the manway, the wing-nut of each unit is turned in a counterclockwise direction. This will cause the hook 24 to be fed downwardly with relation to the body of the wing-nut and flange 3 until shoulder 30 of hook unit 24 engages the inner end 23 of the set-screw 22. At this time the axial movement of the hook unit is arrested and because of the binding action between shoulder 30 and the inner end of the set-screw the hook 24 will swing free of flange 3 to the position shown in Fig. 6. Upon reassembly of the cover rotation of each hook unit will result in the hook 24 of the unit swinging beneath flange 3 due to the established binding engagement of shoulder 30 with set-screw or abutment 22.

The invention provides a structure for attaching a cover in place wherein a positive means is employed to rotate the hook units and swing the hook portion of the unit to positions either beneath or removed from the flange of the structure with which the cover is employed.

Various embodiments of the invention may be employed within the scope of the following claims.

I claim:

1. In a cover assembly for a storage tank or the like having a flange extending circumferentially of an opening in the tank, a cover overlying said opening and extending radially outwardly from said flange, upstanding flange means on said cover, a hollow cover tightening member secured to said cover flange against axial movement but free to rotate, an abutment provided on the inside of the cover tightening member, a clamping member threaded into the cover tightening member, a hook disposed on one end of the clamping member, an abutment provided on the other end of the clamping member adapted to bindingly engage the abutment of the cover tightening member upon relative rotation of the members and effect positive rotation of the hook into and out of position for engagement with the angular flange of the tank, and a second abutment on the clamping member adjacent said hook to engage the tank flange and limit the rotational movement of the hook.

2. In a cover assembly for a storage tank or the like having a circumferentially extending flange surrounding an opening in the tank, a cover overlying said opening and flange, bearing means on said cover projecting radially outward beyond the flange, a nut rotatably secured to said bearing means, an abutment on said nut, a clamping member extending through the bearing means and threaded into the nut, a hook at one end of the clamping member, a shoulder at the other end of the clamping member adapted to bindingly engage the abutment on the nut upon the initial unclamping rotation of the nut to effect positive rotation of said hook out of and into position for engagement with the flange of the tank, and a lug on the clamping member adapted to engage the edge of the tank flange and limit the rotational movement of the hook to a positive locked or unlocked position.

3. The combination of a clamp and cover for use in connection with a storage tank or the like having an annular flange extending circumferentially of an opening for the tank which comprises a cover for said opening having an upstanding circular cup extending axially of said cover, an interiorly threaded cover tightening member wing shape disposed within said cup, said tightening

member being free to rotate within said cup but restricted in axial movement therein, a clamping member threadedly disposed within the tightening member, a hook disposed at one end of the clamping member and adapted to bear against the annular flange of the tank, an abutment disposed at the opposite end of the clamping member, and a set screw threaded through the side of said tightening member and extending inside the tightening member beneath the abutment on the clamping member to limit longitudinal movement of the clamping member downwardly and bind the clamping member to the cover tightening member to effect swinging movement of the clamping hook into and out of position for engagement with the annular flange of the tank.

4. The combination of a clamp and cover for use in connection with a storage tank or the like having an annular flange extending circumferentially of an opening for the tank which comprises 20 a cover for said opening having an upstanding circular cup extending outwardly of said cover, a nut having an interiorly threaded body dis-

posed within said cup, a threaded clamping member disposed within the nut body and disposed to move longitudinally upon rotation of the nut, a hook disposed at the lower end of the clamping member, means to prevent longitudinal movement of the nut, an abutment on the upper end of the clamping member, a second abutment disposed in said nut to limit longitudinal movement of the clamping member and bind the clamping member to the nut to effect swinging movement of the clamping hook into and out of position for engagement with the annular flange of the body, and a stop on the clamping member adjacent said hook to engage the tank flange and limit the rotational movement of the hook.
